Inventor
Earl V. Gara

By
Emmet A. Moore, Atty.

UNITED STATES PATENT OFFICE.

EARL V. GARA, OF BALBOA, CALIFORNIA.

EXHAUST AND WATER DISCHARGE FOR ENGINES.

Application filed March 28, 1921. Serial No. 456,428.

To all whom it may concern:

Be it known that I, EARL V. GARA, a citizen of the United States, residing at Balboa, in the county of Orange, State of California, have invented new and useful Improvements in Exhaust and Water Discharge for Engines, of which the following is a specification.

My invention relates to exhaust and water discharge construction for internal combustion engines, and is particularly adapted to be used in connection with marine engines.

In engines of the type above described it has been customary to discharge the exhaust products through a pipe leading rearwardly from the engine along the bottom of the boat and having its exit at the stern thereof a short distance above the water line. It has also been customary to lead the water from the cooling jacket into this pipe to be discharged into the sea along with the exhaust products. In this construction an upwardly projecting arch in the shape of an inverted U is formed in the exhaust pipe adjacent the engine, in order that when the boat pitches the water would not run forwardly through said exhaust pipe into the cylinders and thereby foul the engine, the pipe from the cooling jacket entering the exhaust pipe at the rear of said arch.

The foregoing described construction has proven objectionable, inasmuch as not only a vast amount of heat is thrown out into the boat by the arched pipe, to the discomfort of the occupants of the boat, as well as subjecting the boat to the danger of fires, as the arch at times become red hot, but while the engine is not in operation moisture finds its way through the exhaust pipe into the engine cylinders to the detriment of the efficient functioning of the engine.

It is the object of my present invention to provide a construction which will overcome the above recited objections, by discharging the exhaust products as well as the water from the cooling jacket at a point high above the level of the sea and at the same time utilizing the water from the cooling jacket for cooling the exhaust pipe, and so arranging the various discharge pipes that all danger of water backing into the engine cylinder is eliminated.

A further object of my invention is to provide means whereby the pump for supplying the engine cooling jacket with water,

may be readily and conveniently primed should the water in said cooling jacket become exhausted when the engine is out of use, due to a leaky foot valve in the pump.

Other objects of my invention will be disclosed in the following description, and pointed out in the claims, and are embodied in the accompanying drawings, in which:

Fig. 1 is a side view of a boat, parts being broken away to show the engine and the elements of my invention applied thereto.

Fig. 2 is an enlarged detail sectional view, illustrating more clearly the construction and operation of my invention.

In carrying out my invention, 5 represents a boat, having the bow 6 and the stern 7. The propeller 8 is mounted on the shaft 9 which is driven in the usual manner by the engine 10. The engine 10 is provided with the usual exhaust manifold 11, the pump 12 which sucks water from the sea to supply the cooling jacket 13, and the fuel inlet manifold 14.

My improved discharge construction comprises a tubing 15 of suitable length and diameter which is adapted to be supported in an upright manner and is provided at the top with a water tight cap 16 and at its lower end with a water tight fitting 16'. The fitting 16' is provided with a downwardly projecting elbow 17 into the lower end of which is threaded the end 18 of the exhaust manifold 11. The opposite end of elbow 17 projects upwardly into tubing 15 and threaded into the same is a pipe 19 of smaller diameter than tubing 15 which forms a continuous passage for the exhaust products.

The pipe 19 extends upwardly into tubing 15, its upper end being open, and terminating adjacent the lower surface of cap 16, and may be provided with a plurality of perforations 20 as clearly shown in Fig. 2 of the drawings.

The cooling jacket 13 of the engine, is connected to the chamber 21 formed between the outer wall of pipe 19 and the inner wall of tubing 15 adjacent the lower end of said tubing, by means of a pipe 22 which is provided with a valve 23; and the upper end of chamber 21 is provided with an outlet opening 24 tapped into the wall of said tubing, into which may be secured the discharge pipe 25 adapted to lead to the outside of the boat at a suitable distance above

the water line. The opening 24 is arranged in the wall of casing 15 a suitable distance below the level of the perforations 20, in order that when water is admitted into the chamber 21 it will pass out through the pipe 25 before it reaches the level of said perforations, thus preventing an over-flow into pipe 19.

In the operation of the apparatus the valve 23 is opened, the engine is then started, which in turn starts the pump 12, water is thereby pumped through the cooling jacket 13, thence through pipe 22 into chamber 21. The exhaust products from the engine pass through pipe 18 into pipe 19 and thence through the top of said pipe and the perforations 20. As the water from the cooling jacket reaches approximately the level of the discharge opening 24 the exhaust products force the water out through the pipe 25, said products discharging at the same time through said pipe.

By the above described mode of operation it will be seen that the water from the cooling jacket tends to keep the exhaust pipe cool and by the mixing of the exhaust products with the water and discharging them simultaneously the water forms a cushion for the exhaust products and thereby deadens the sound and forms an efficient muffler. It will also be noted that the force of the discharge products effectively prevents any of the water from entering the exhaust pipe 19 to foul the engine.

Should the foot valve (not shown) of the pump 12 be defective or leaky, it will be obvious that when the engine is idle the cooling jacket of the engine will become drained and when the engine is again started the pump will have to be primed in order that it may properly function; to this end the valve 23 is provided in pipe 22 and if closed immediately after the engine is stopped sufficient water will become trapped in chamber 21 to be utilized for priming the pump when it is again desired to start the engine.

What I claim is:

1. The combination with an internal com-

bustion engine having a cooling jacket provided with water inlet and outlet openings and a pump for circulating water through said cooling jacket, of a stand pipe connected at its lower end with said water outlet opening and provided adjacent its closed upper end with a discharge opening, and a second stand pipe of smaller diameter arranged in said first mentioned stand pipe adapted to be connected with said engine exhaust manifold, said second mentioned stand pipe being open at its upper end and extending above said discharge opening.

2. The combination with an internal combustion engine having a cooling jacket provided with water inlet and outlet openings and a pump for circulating water through said cooling jacket, of a stand pipe connected at its lower end with said water outlet opening and provided adjacent its closed upper end with a discharge opening, a second stand pipe of smaller diameter arranged in said first mentioned stand pipe adapted to be connected with said engine exhaust manifold, said second mentioned stand pipe being open at its upper end and extending above said discharge opening, 70 and a valve for closing connection between said stand pipe and water outlet opening.

3. The combination with an internal combustion engine, of an exhaust pipe connected with the exhaust port of the engine cylinder, the free end of said exhaust pipe opening to atmosphere, a cylindrical water jacket surrounding the outer portion of said exhaust pipe, said jacket having closed ends, and a valve controlled water passage connected to the lower end of said cylindrical water jacket and to the water jackets of the engine cylinder, said cylindrical water jacket having a discharge passage at the upper end thereof, the water from the engine jackets and the products of combustible discharging through said discharge passage.

In witness that I claim the foregoing I have hereunto subscribed my name this 7th day of March, 1921.

EARL V. GARA.
